Specification for Design.

Patented Apr. 17, 1917.

Application filed February 2, 1917. Serial No. 146,288. Term of patent 3½ years.

To all whom it may concern:

Be it known that I, IRVING BROMILEY, a citizen of the United States, residing at Cranston, in the county of Providence and State of Rhode Island, have invented a new, original, and ornamental Design for a Sign, of which the following is a specification.

In the accompanying drawings which form a part of this specification,

Figures 1 and 2 are front and end eleva-

tions respectively of a sign embodying my new design.

I claim:

The ornamental design for a sign as shown.

IRVING BROMILEY.
